Attorney.

UNITED STATES PATENT OFFICE.

GLADYS I. LAY, OF LOS ANGELES, CALIFORNIA.

DESIGN FOR AN INCENSE-BURNER.

59,556.

Specification for Design.

Patented Nov. 1, 1921.

Application filed June 21, 1921. Serial No. 479,390. Term of patent 3½ years.

To all whom it may concern:

Be it known that I, GLADYS I. LAY, a citizen of the United States, residing at Los Angeles, in the county of Los Angeles and State of California, have invented a new, original, and ornamental Design for an Incense-Burner, of which the following is a specification, reference being had to the accompanying drawing, forming a part thereof, in which—

Figure 1 is a perspective view showing the front portion of the incense burner; and

Fig. 2 is a view in perspective showing the back portion thereof.

The characteristic feature of my present design resides in a figure representing a Chinese boy loosely seated on a base with the knees drawn up and the elbows resting on the knees, with the forearms extending up-

wardly and supporting the chin; the figure being decorated to represent Chinese attire. The feet are formed with Chinese shoes and a bandeau is formed on the head. The representation of a Chinese boy is further strengthened by forming a "pig-tail" on the back of the figure. The eyes and eyebrows are slanted to give the face the Chinese expression. The mouth is rounded and open to form an outlet leading from the hollow interior of the figure through which incense fumes generated within the figure may pass or to form a socket to hold stick incense.

I claim:

The ornamental design for an incense burner, substantially as shown and described.

GLADYS I. LAY.
